TRAY FOR A WRAPPED FRUIT CONTAINER

Joseph E. Murphy, Hicksville, and Murray Schnall, Brooklyn, N. Y., assignors to See-Qual Package Corp., New York, N. Y., a corporation of New York

Application November 19, 1954, Serial No. 33,167

Term of patent 14 years

(Cl. D58—26)

FIG. 1.

FIG. 2.

FIG. 3.

The dominant feature of our design resides in the configuration and appearance presented by the bottom portion of the tray as best seen in Fig. 1.

We claim:

The ornamental design for a tray for a wrapped fruit container, substantially as shown and described.
